ABSTRACT

A machine for straightening an elongated workpiece including a base, a first series of axially spaced rolls mounted on said base, a second series of axially spaced rolls mounted in contiguous relationship to the first series on a pivotable frame which is pivotally mounted on said base and which includes a counterweight for biasing the second series of rolls toward the first series of rolls, and a third series of axially spaced rolls mounted on a pivotable carrier for movement toward and away from the first and second series of rolls so as to permit a workpiece to be admitted between the three series of rolls when the third series is in an away position and to thereafter move into engagement with the workpiece so that it is rolled by the three series of rolls and thereafter pushed through the space between the first and second series as a result of the continued movement of the third series of rolls toward the first and second series. The three series of rolls may include rolls having a steel hub and a plastic rim. Alternately the rolls may be fabricated entirely from plastic material. Electric circuit means are provided so as to pass an electric current through a workpiece while it is being rolled for testing purposes.

FIG. 22.

STRAIGHTENING MACHINE FOR ELONGATED WORKPIECES

The present invention relates to an improved machine for straightening elongated wire-like workpieces by bending between rolls.

In copending application of John F. Kopczynski, Ser. No. 812,534, filed on Mar. 7, 1969, now U.S. Pat. No. 3,625,263, a basic straightening machine was disclosed which bent an elongated workpiece by means of three series of rolls which were circumferentially spaced about the workpiece. The machine of the present invention is an improvement over a machine of the foregoing type.

It is accordingly one object of the present invention to provide an improved straightening machine which will rotate an elongated workpiece about its own axis with good traction to effect straightening thereof without marring the workpiece.

Another object of the present invention is to provide an improved bending machine for straightening an elongated workpiece in which the various circumferentially spaced series of rolls between which the workpiece is straightened are generally yieldable in the event of a jamming of the workpiece so as to prevent injury to the machine. A related object of the present invention is to provide an improved straightening machine in which the rolls themselves are made of yieldable material to yield in the event of misalignment of the workpiece so that jamming of a workpiece between the rolls can be avoided. A further related object of the present invention is to provide an improved combing arrangement associated with the rolls to comb out any workpieces which may be jammed between the yieldable rolls, the yieldable rolls permitting release of a jammed workpiece due to the yielding nature of the rolls themselves, without injury to the rolls. A further related object of the present invention is to provide an improved straightening machine in which certain of the series of rolls can be separated quickly and easily from other of the series to provide access to the spaces between them, thereby to facilitate removal of workpieces which may become jammed in the rolls and to facilitate inspection and replacement of rolls.

A further object of the present invention is to provide an improved straightening machine which can test a conductive workpiece during the process of straightening it so that both the straightening and the testing can be performed simultaneously. A related object of the present invention is to provide an improved straightening machine in which workpieces which do not test within acceptable limits may be intercepted when they are discharged from the straightening rolls. Other objects and attendant advantages of the present invention will readily be perceived hereafter.

The improved straightening machine of the present invention includes a base, a first series of axially spaced rolls mounted on the base, a second series of axially spaced rolls mounted on a frame member which is pivotally mounted on the base so as to cause the second series of rolls to be capable of movement toward and away from the first series of rolls, a weighted member on the frame member urging the second series of rolls toward the first series of rolls, a third series of rolls mounted in contiguous relationship to the first and second series of rolls and adapted to be moved into radial overlapping relationship therewith, an oscillatable pivotal carrier mounted on the base and cyclically carrying the third series of rolls toward and away from the first and second series from a remote position wherein a workpiece is dropped between the three series of rolls to a position wherein it bends the workpiece in conjunction with the other two series of rolls and thereafter forces the workpiece out from between the first and second series of rolls by causing the pivotable frame member to yield when the workpiece is pushed between the first and second series of rolls. The rolls can be of any material but preferably are either fabricated entirely of a resilient plastic material or comprise plastic rims mounted on metal cores. A comb arrangement may be provided between certain of the rolls to comb out any workpieces which may be stuck therebetween. Furthermore, means may be provided in as-

sociation with the rolls for conducting an electric current through a workpiece for testing purposes simultaneously with the rolling.

The various aspects of the present invention will be more fully understood when the following portions of the specification are read in conjunction with the accompanying drawings wherein:

FIG. 1 is a fragmentary side elevational view of one embodiment of the improved straightening machine of the present invention;

FIG. 2 is a fragmentary plan view of the machine of FIG. 1 with certain parts omitted in the interest of clarity;

FIG. 2a is a fragmentary plan view of the weighted portion of the upper pivotable frame of the machine;

FIG. 3 is a diagrammatic view showing the positions the various series of rolls of the machine assume during loading of the workpiece;

FIG. 4 is a view similar to FIG. 3 but showing the positions the series of rolls assume during the straightening of the workpiece;

FIG. 5 is a view similar to FIG. 4 but showing the positions which the series of rolls assume during the discharge of the workpiece after it has been straightened;

FIG. 6 is a fragmentary front elevational view with parts omitted in the interest of simplicity showing an embodiment which includes rolls having conductive peripheries for passing a current through a workpiece being straightened;

FIG. 7 is a fragmentary cross sectional view of the straightening rolls used in all of the preceding embodiments having an annular plastic rim or tire mounted on the metal central portion thereof;

FIG. 8 is a cross sectional view showing the manner in which an outer conductive silver ring is mounted on a metal roll with an insulating ring therebetween for the purpose of conducting electricity to a workpiece;

FIG. 9 shows a roll which is made entirely of plastic and can be substituted in the embodiment of FIG. 6 for rolls such as those shown in FIG. 7;

FIG. 10 is a fragmentary side elevational view showing keyways milled across the faces of the rolls such as shown in FIG. 7 for the purpose of receiving cement to provide a good tight bond between the cement and the roll to prevent slipping of the outer peripheral rim portion;

FIG. 11 is a fragmentary side elevational view showing the manner in which the outer silver rim of FIG. 8 is secured to the plastic insulating ring;

FIG. 12 is a schematic view showing a roll configuration with end rolls omitted for the purpose of permitting a bent wire to rotate during straightening without being crushed by rolls in this area;

FIG. 12a is a schematic view similar to FIG. 12 but showing another roll arrangement with the rolls of each series being of alternating smaller and larger diameter and the end rolls being composite rolls of smaller and larger diameter to prevent catching of a bent end portion of a wire therebetween;

FIG. 13 is a view showing a cascading type of delivery chute associated with the exit side of the straightening machine and including a motor operated gate arrangement for intercepting rejects and dumping them into a receptacle;

FIG. 14 is a schematic view of a control arrangement which may be associated with the gate assembly of FIG. 13 and also shows a straightened electronic component, such as a diode, located between the rolls of the machine;

FIG. 15 is a fragmentary side elevational view of an alternate embodiment of the present invention, partially in cross section, and showing especially an arrangement of a frame structure which permits the driving gears to be placed in a substantially straight line, this figure also showing combs between the rolls of certain of the series of rolls for removing workpieces which may be jammed between the rolls;

FIG. 16 is a schematic view of the relationship between the driving gears of the embodiment of FIG. 15;

FIG. 17 is a cross sectional view taken generally along line 17-17 of FIG. 15 and showing the configuration of the combs and also showing insulation mounted on the sides of the pivotable top frame of the machine;

FIG. 18 is a fragmentary cross sectional view showing the shaft assembly which may be used for mounting various of the series of rolls;

FIG. 19 is a side elevational view of a preferred arrangement of a series of rolls which is fabricated from machined polyurethane and includes a metal liner hub;

FIG. 20 is a side elevational view of a preferred mating roll series for use with the rolls series of FIG. 19;

FIG. 21 is a view of the third roll series used with the roll series of FIGS. 19 and 20; and

FIG. 22 is a side elevational view, partially in cross section, of a bending machine similar to the machine of FIGS. 1 and 2 and showing a cam arrangement for cyclically varying the space between the first and second series of rolls.

The straightening machine 10 of FIGS. 1 and 2 includes a base 11 having a drive shaft 12 suitably journalled thereon which is driven from a suitable motor source (not shown) which may be a motor mounted relative to base 11 or a belt drive. Keyed to shaft 12 is a sprocket wheel 13 which is engaged by toothed belt 14 which in turn also engages toothed sprocket wheels 15 and 16. Sprocket wheel 15 is mounted on shaft 16' which is journalled in standards 17 and 18 extending upwardly from base 11. Sprocket wheel 16 is mounted on shaft 19 which has opposite ends thereof journalled in standards 20 and 21 extending upwardly from base 11 on opposite sides of the machine. Effectively keyed to shaft 19 are spaced rolls or discs 22 which are separated by spacers (not shown) which are analogous to the spacers on the other shafts described hereafter. It will be appreciated that as shaft 19 is driven by belt 14, rolls 22 will be driven with it. The exact structural characteristics of rolls 22 will be described in greater detail hereafter.

A pivotable upper frame member 23 includes an upper elongated arm-like portion 24 (FIGS. 1, 2 and 2a) which extends from rear elongated portion 25 and carries a weight 26 at its end. Spaced arms 27 and 28 extend downwardly from portion 25 and are pivotally mounted on pins 29 and 30, respectively. Pin 29 extends through arm 27 and standards 21 and 21' which extend upwardly from base 11. Pin 30 extends through arm 28 and standards 20' and 20'' which extend upwardly from base 11. Pins 29 and 30 are held in position by retaining screws 31 and 32. It can readily be seen that frame 23 can thus pivot about the centers of aligned shafts 29 and 30. Coaxially mounted on shaft 30 is an idler gear 33 which is driven by gear 34 keyed to shaft 19. Idler gear 33 drives gear 35 which is keyed to shaft 36 which is journalled in arm 28 on one side of the machine and in arm 27 on the other. Thus shaft 36 will pivot with frame 23. It is to be noted that since idler gear 33 is mounted coaxially with the center of pivotal movement of arms 27 and 28, there is a driving relationship between gears 34, 33 and 35 without frictional resistance which would otherwise be occasioned by pivotal action of frame 23. A plurality of disc-like rolls 37 are keyed to shaft 36 with spacers 38 therebetween. Rolls 37 are in axial alignment with disc-like rolls 22 keyed to shaft 19, as can best be seen from FIG. 2. The exact relationship between rolls 22 and 37 will be described in greater detail hereafter.

A carrier frame 40, includes a lower arm-like portion 39, pivotally mounted on shaft or pin 41 which is mounted in opposed standards 20 and 21. The upper part of carrier 40 includes spaced portions 42 and 43 which journal the ends of shaft 44 on which disc-like rolls 45 are mounted with spacers 46 therebetween. An ear 47 extends outwardly from the central portion 39 of carrier 40 and it receives pin 48 which also extends through spaced legs 49 of U-shaped bracket 50 to effect a pivotal mounting therewith. A screw-like member 51 in the nature of a turnbuckle has oppositely threaded portions 52 and 53 which are received in mating tapped holes in bracket 50 and block 54. It will be appreciated that when screw 51 is

turned, the distance between bracket 50 and block 54 can be varied by causing them to approach or recede from each other. Block 54 in turn is pivotally mounted on crank pin 55 which is eccentrically mounted on disc 56 which is driven by shaft 16'. Thus, block 54 is eccentrically mounted to cause oscillation of U-shaped member 50 back and forth to thus cause carrier 40 to oscillate back and forth about shaft 41 and thus cause the series of rolls 45 to move toward and away from the series of rolls 22 and 38.

10 The component which is to be straightened by machine 10 may be a diode 57 such as shown in FIG. 14 which includes a central portion 58 and wires 59 extending from opposite sides thereof. During the fabrication process of components 57, wires 59 are usually bent into shapes other than straight members. However, as a final process it is desirable to have these straight and in alignment with each other and it is for this purpose that the machine of FIGS. 1 and 2 is used. However, it will be appreciated that the present machine may be used for straightening any type of wire or rod-like member.

15 In order to load components 57 into machine 10 any suitable type of loading arrangement may be used which may include a cascading type of feed hopper such as 60 shown in FIG. 13. While hopper 60 is shown on the outlet side of the machine in FIG. 13, it will be appreciated that it can be used in conjunction with the inlet side of the machine in FIG. 1.

20 During oscillation of carrier 40 a point will be reached when the series of rolls 45 (FIG. 3) are in a position which is as far to the left as they will go. At this time there is a space 61 between roll 45 and 37 and it is into this space that component 57 is dropped and it will come to rest at the vertex 62 between rolls 22 and 37. Thereafter, the oscillation of carrier 40 will move rolls 45 in a clockwise direction to the position shown in FIG. 4 wherein rolls 22, 45 and 37 engage wires 59 to straighten them. Continued movement of carrier 40 in a clockwise direction will cause it to move rolls 45 to the position shown in FIG. 5 wherein they force component 57 through the space between rolls 22 and 37 so that it will drop outwardly as shown by arrow 63.

25 30 35 40 As noted above, rolls 37 pivot about the axis of shafts 30 and 29 because rolls 37 are mounted on frame 23. Frame 23 will be caused to pivot in a clockwise direction when rolls 45 force workpiece 57 through rolls 22 and 37. The yielding action of rolls 37 which is thus obtained produces sufficient clearance between rolls 37 and 22 to permit the workpiece 57 to pass therebetween. Before the pivoting movement of frame 23 the clearance between rolls 22 and 37 is insufficient for workpiece 57 to pass therebetween. The amount of resistance to the pivotal movement of frame 23 is determined by the weight of counterweight portion 26 mounted at the outer end of arm 24 and this weight may be changed for different workpieces. Furthermore, the amount of initial clearance between rolls 37 and 22 is determined by the position of bumper 64

45 50 55 60 65 which can be adjusted upwardly or downwardly by turning said bumper which is mounted on a screw 65 which is received in standard 18. Nut 66 secures bumper 64 in its adjusted position. The counterbalance provided by weight 64 also permits the yielding of frame 23 and rolls 37 in the event for some reason there is a jamming due to the workpiece 57 being caught between the rolls. Furthermore, the use of a pivotal frame 23 also facilitates quick and easy manual movement of the rolls 37 away from rolls 22 and 45 in the event there is a jamming of any sort, or for inspection or replacement.

65 70 75 The relationship between rolls 22, 37 and 45 may be the same as any of the relationships discussed in detail in copending application of John F. Kopczynski, Ser. No. 812,534, filed Mar. 7, 1969, and now U.S. Pat. No. 3,625,263. In this respect, as can be seen from FIG. 12, rolls 37 may be in axial alignment with rolls 22, this also being shown in FIG. 2. Furthermore, rolls 37 may all be of the same diameter; and rolls 22 may be of the same diameter. In FIG. 12 there is a space 67 at the end of the series of rolls. In the event that the workpiece has a bent end 68, it will be permitted to whip around without being wedged in between any of the rolls 22,

37 or 45. From FIGS. 12 and 2 it can be seen that the central portion 58 of the workpiece will be supported by roll 68' so that it does not whip around excessively. If desired, roll 68' may be of such a dimension that it tends to overbend the portions of wires 59 which are adjacent to central portion 58. This is done by making roll 68' of a size wherein it tends to press portion 58 toward the exit space between rolls 22 and 37 and this being the case it will be appreciated that as portion 58 rotates it will tend to produce a bending action on the portions of wires 59 adjacent thereto.

In FIG. 12a another arrangement of rolls is shown. In this arrangement there are rolls 37 and 37' coaxially mounted on one of the shafts such as 36. Rolls 37' are of slightly smaller diameter than rolls 37. Coaxially mounted on a shaft such as 19 are rolls 22 and 22'. Rolls 22' are of slightly smaller diameter than rolls 22. As can be seen from FIG. 12a, rolls 22' are opposed to rolls 37, and rolls 37' are opposed to rolls 22. Rolls 45 are the same as rolls 45 of FIG. 12 and bear an analogous relationship to the remainder of the rolls with which they are associated. Rolls 45 are all of the same diameter, and, as shown, are of slightly larger diameter than the other two series of rolls. By virtue of the fact that smaller diameter rolls are in opposition to larger diameter rolls in the embodiment of FIG. 12a, as the workpiece is rotated, the axial portions on wires 59 will be bent back and forth to provide an overbending action and thus erase any "memory" of the wire which would tend to return it to its original shape after straightening was completed. It will be appreciated that the overbending occurs during the time that maximum pressure is exerted on the workpieces and as such pressure is relieved the straightening action is effected. As the workpiece leaves the rolls while they separate, the overbending action will diminish and the wires will remain in a straightened condition. The basic concept behind this particular arrangement for straightening wires or other elongated workpieces was set forth in greater detail in the above mentioned copending application Ser. No. 812,534, now U.S. Pat. No. 3,625,263.

It is to be noted that the embodiment of FIG. 12a includes end rolls 70 and 71 coaxially mounted on a shaft such as 36 and end rolls 72 and 73 coaxially mounted on a shaft such as 19. All of these end rolls are composites in that they each have a smaller diameter portion which is equal to the diameter of either rolls 37' or 22' and a larger diameter portion which is equal to the diameter of rolls 22 or 37. The smaller and larger diameter portion of each composite roll are coaxial. Between these smaller and larger portions on each composite roll is a merging portion which merges the larger diameter portions to the smaller diameter portions. These composite rolls 70-73 are capable of providing an overbending action in the same manner as the single rolls with which they are associated. The advantage of these composite rolls is that a bent end such as 68 shown in FIG. 12 cannot be caught between adjacent smaller and larger rolls because these spaces are nonexistent in that they are filled by a portion which merges the smaller diameter roll portions to the larger diameter roll portions.

In accordance with one embodiment of the present invention, all of the rolls described above, namely, rolls 22, 37 and 45, as well as rolls 22' and 37' are fabricated from a steel central hub portion and mount a plastic rim or tire, which in this case is comprised of polyurethane having a shore hardness of 75 on the B scale. However, it will be appreciated that any other suitable plastic or non-metal rim can be used. In the embodiments shown, rolls 37 (FIG. 7) include a steel hub 74 and mount a polyurethane ring or tire 75 on their outer periphery. Rolls 45 each include a steel hub or core 76 and mount a plastic rim or tire 77 on its peripheries. Rolls 22 each include a steel hub or core 78 and mount a plastic rim or tire 79 on its peripheries. While the structural details of construction are shown only for rolls 37 (FIG. 7), it will be appreciated that rolls 22 and 45 have analogous constructions. The advantages of effecting the bending by means of plastic peripheries on the rolls is to provide improved traction; provide greater resilience so as not to damage the workpiece by permitting the

plastic tires to yield in the event that the workpieces are oversize; and also to provide electrical insulation between the wire being straightened and the rolls. The cross section of rolls such as 22 and 37 and 45 are shown in FIG. 7 wherein the plastic tire or rim 75 is secured to core 74 by means of epoxy cement 80 which is held within an annular groove on the periphery of core or hub 74. A preferred construction for retaining outer rim or tire 75 on core 74 is shown in FIG. 10 wherein the epoxy cement 80 not only lies in annular groove 81 but also fills out milled slots 82 which extend across the opposed spaces of core 74. Thus, in essence the epoxy adhesive forms keys 83 which are integral with the band 80 of the epoxy adhesive to thereby provide added resistance against slipping of the adhesive. If desired, all of the rolls such as 22, 37 and 45 may be fabricated completely of suitable plastic such as the polyurethane discussed above. Such rolls are shown at 84 in FIG. 9.

It is also within the scope of the present invention to provide apparatus for testing the workpieces, such as components 57, while their wire portions 59 are being straightened. The apparatus for effecting such testing is partially shown in FIG. 6 wherein a plurality of rolls such as 22'', which are analogous to rolls 22 of FIG. 1 are mounted on a shaft 19' extending between spaced standards 85 and 86. Rolls 22'' may be identical in construction to the rolls described above in FIGS. 3-5 and 7-9. However, at the outer end portions of shaft 19' rolls 87 are mounted (FIG. 8). These rolls 87 include a steel hub or core 88 mounting an insulating plastic ring 89 which in turn mounts an outer silver band 90. As can be seen from FIGS. 8 and 11, plastic band 89 is secured to core 88 by means of epoxy adhesive 91 which forms an annular band in annular groove 92 of hub 88. Keyways 93 are formed in hub 88 to receive epoxy cement and thus prevent ring 91 from slipping. The outer silver ring 90 is secured to the outer surface of an annular band 89 in an analogous manner by providing an annular groove 94 in insulating ring 89, said groove receiving an annular ring of epoxy cement 95 therein. Furthermore, cylindrical holes 96 are drilled through silver band 90 from side to side to receive the epoxy cement and thus effectively provide keys for preventing slipping of said band relative to ring 90.

As can be seen from FIG. 6, insulating blocks 97 and 98 mount conductors 99 and 100, respectively, which engage silver rings 90. Electrical leads 101 conduct electrical current to conductors 99 and 100. It will readily be appreciated that as shaft 19' rotates, continuous electrical contact will be maintained with rings 90 of rolls 87 through the above described structure. When a workpiece, such as 57, is placed in bridging relationship between rolls 87, as shown in FIG. 14, electrical current can be passed through it while it is being subjected to the straightening action. During this time information can be obtained as to its electrical resistance characteristics so that in the event that it does not test properly, appropriate action can be taken. It will further be appreciated that if for any reason the workpiece should require heating during the straightening, this can be effected by applying current thereto by the use of the same type of apparatus as shown in FIGS. 6 and 14.

A modified arrangement of the subject matter of FIG. 6 is shown in FIG. 14 wherein a control arrangement 102 is provided for applying electric current to conductors 99 and 100 by means of leads 103 and 104. The analyzing controller 102 also includes required electric circuitry which will measure the resistance of the workpiece 57. If it falls within certain limits, it will be permitted to drop out from between the rolls, in the manner shown in FIG. 5, without being intercepted. However, if for any reason it does not measure up to specifications, solenoid valve 105 will be energized to cause compressed air to be supplied to air motor 106 from supply line 107 through conduit 108. This will cause piston 109 to move upwardly against the bias of spring 110 to pivot gate 111 about axis 112 from its solid line position shown in FIG. 13 to its dotted line position. This will cause the rejected workpiece to land on gate 111, and thereafter when it returns to its solid line position the workpiece will fall into receptacle 113 attached to the side of the machine by means of brackets 114.

As can be seen from FIG. 13, a cascade outlet chute 115 is provided at the outlet of the rolls. This cascading outlet includes a plurality of elongated members 116 and 117 which have length extending perpendicular to the plane of the drawing which is at least as long as workpiece 57 so that as the workpieces drop down, they will contact each of these cascading elements downwardly in sequence so as to tend to straighten the workpiece so that it eventually falls in a perfectly horizontal attitude. This facilitates the stacking of the workpieces.

It will be appreciated that the control arrangement can be very rudimentary if the machine is to be operated slowly. In this respect, an ohmmeter can be placed in lines 103 or 104 and the resistance of the workpiece can be measured during bending. If it falls within an acceptable range it can be permitted to pass into delivery chute 60. If the reading is outside of the acceptable range, a valve such as 105 can be actuated manually to swing gate 111 to an intercepting position.

In FIGS. 15-18 another embodiment of the present invention is disclosed. This embodiment encompasses the same basic principles of operation as the embodiments of FIGS. 1 and 2. Furthermore, it can mount any of the rolls of the types enumerated above. Basically, this embodiment has two features which are not shown in the preceding drawings. The first feature is that the drive train is practically horizontal so that the equipment may be built lower. In this respect a belt 120 extends from a source of motion such as an electric motor (not shown) and encircles sprocket 121 mounted on shaft 122. A gear 123, which shown in FIG. 16 but not in FIG. 15, is mounted on shaft 122 and is in mesh with a gear 124 mounted on shaft 125. Gear 124 in turn is in mesh with gear 126 which is mounted on shaft 127 which also mounts rolls such as 22 of FIG. 1 and end rolls 87 such as described above in FIGS. 8 and 14. Gear 126 is in mesh with idler gear 128 which is mounted on shaft 129 journaled on the wall 130 of the machine. Gear 128 in turn is in mesh with gear 131 mounted on shaft 132 which also mounts rolls such as 37 described above. A carriage 133 is pivotally mounted on shaft 134 secured to wall 130. Carriage 133 is analogous to carriage 40 of FIG. 1 and operates in the same manner, namely, by being pivoted to link 134' about pivot 135, link 134' including an adjusting turn-buckle-like mechanism 136 which is secured to block 137 which is pivotally mounted on pin 138 located in eccentric driving relationship with shaft 122. It will thus be seen that carriage 133 will oscillate back and forth like carriage 40 of FIG. 1. The limit of oscillation in a clockwise direction will be controlled by the adjustment of screw 139, the lower end of which abuts ledge 140.

The upper pivotable frame 141 of the machine may be identical to that shown in FIG. 1 and designated as upper frame 23. This frame includes a counterweight portion 142 at the outer end thereof which mounts screw 143 carrying bumper 144. By the adjustment of bumper 144, the at rest position of upper frame 141 can be adjusted, and with this the adjustment of rolls 37 inasmuch as shaft 132 is mounted between spaced ears 145 which are pivotally secured to base 130 by pins 129. One pin 129 extends through spaced standards 130 and 155' and the other ear extends between spaced standards 130 and 154' (FIG. 17). Rolls such as 45 are mounted on shaft 146, the opposite ends of which are journaled in spaced ears 147 forming a part of carriage 133, ears 147 being analogous to members 42 and 43 of FIG. 2.

Plastic plates 148 line the sides 149 and 150 of upper pivotal frame 141. Hopper portions 151 and 152 extend between plates 148 to guide the workpieces downwardly into working position between the rolls. Side plates 148 are fabricated from plastic so that the workpieces will be insulated from the metal parts of the machine. Furthermore, as can be seen from FIG. 15, the side plates 148 are of a modified hour-glass configuration and include a left edge 153 and a right edge 154 and a bottom edge 155. It will be appreciated that hopper 156 can be built in the form of a cascader such as 60 shown in FIG. 13 so as to automatically align the workpieces in a horizontal attitude for proper delivery to the rolls.

An arrangement is shown for mounting a shaft such as 127 on the side walls 130 of the machine. The mounting consists of shaft 127 having bearing 156 and 157 mounted thereon and held against outward movement by C-rings 158. Proximate bearing 156 is a gear such as 126 which is held in position by a nut 159. On the opposite side of shaft 127 a nut 160 is threaded which is locked in position by a set screw 161.

In FIGS. 19, 20 and 21 preferred alternate types of roll assemblies are shown. Roll assembly 162 consists of a hollow annular metal sleeve 163 pressed within hub 164 which is formed integrally with rolls or discs 165, 166, 167, 168 and 169. The entire roll arrangement which is mounted on sleeve 163 is fabricated from a block of polyurethane material having a shore hardness of 75 on the D scale by suitable machining procedures. It can be seen that rolls 165 are of smaller diameter than rolls 166. In a model that was actually made the diameter of rolls 165 was 2.490 inches and the diameter of rolls 166 was 2.510 inches. The outer rolls 167 are also of a diameter of 2.510 inches. Rolls 168 and 169 are composite having portions 168' and 169' which are of the above mentioned smaller diameter and portions 168'' and 169'' which are of the above mentioned larger diameter. Roll assembly 162 is intended to be mounted in the machine such as shown in FIG. 1 on a shaft such as 19. It will be appreciated that the roll assembly 162 can be made of any suitable plastic material.

In FIG. 20 a roll assembly 170 is shown which is adapted to be mounted in a location in FIG. 1 as on shaft 36. Assembly 170 includes smaller diameter rolls 171 and larger diameter rolls 172, with rolls 171 being of the above mentioned 2.490 inch diameter and rolls 172 being of the 2.510 inch diameter. It will readily be appreciated that rolls 171, of smaller diameter, are in alignment with rolls 166, of larger diameter, and that rolls 172 of larger diameter are in alignment with rolls 165 of smaller diameter. Furthermore, roll assembly 170 includes composite rolls 173 and 174, as well as outer rolls 175. Rolls 175 are of the above mentioned smaller diameter and they are located in opposition to larger diameter rolls 167 of roll assembly 162. The composite rolls 173 and 174 include smaller diameter portions 173' and 174', respectively, and larger diameter portions 173'' and 174'', respectively. It can be seen that rolls 168 and 169 are in opposition to rolls 173 and 174, respectively, with the larger diameter portions in opposition with the smaller diameter portions. Because of the alignment of the smaller diameter rolls with the larger diameter rolls the overbending action described in detail above is obtained. Furthermore, it is to be noted that the composite rolls 168, 169, 173 and 174 are located at the central portions of the shaft and thus will prevent parts from getting jammed in between separate rolls, if such were used. The roll assembly 170 is fabricated from a block of plastic in the same manner as roll assembly 162.

In FIG. 21 a third roll assembly 177 is shown and this roll is adapted to be mounted in the machine of FIG. 1 on shaft 44 on the swinging carriage 40. This roll is fabricated in the same manner as roll assemblies 162 and 170, namely, it is machined from a block of polyurethane material and is mounted on steel annular sleeve 178 by a press-fit. This roll assembly includes rolls 179 which are of a diameter of 0.2750" throughout the length of the roll and they fit into the spaces between rolls 171 and 172 of FIG. 20 and in the spaces between rolls 165 and 166 of FIG. 19 in the same manner as shown in FIG. 1 relative to the rolls depicted therein. Roll assembly 177 includes a central enlarged roll 180 which is loosely mounted on the hub portion 181 and roll 180 is adapted to engage the portion 58 of workpiece 57 (FIG. 14). It can be seen that a relatively large space 182 exists on both sides of roll 180 to accommodate rolls 173 and 168 on one side and, to also accommodate rolls 169 and 174 on the other side. Because of the existence of spaces 182 it will be seen that there will be clearance for portion 58 of the workpiece in the event if for any reason it is dropped into position and is misaligned so that portion 58 is not engaged by roll 180 but is laterally removed therefrom so that it is engaged by either rolls 173 or 174 or rolls 168 or 169, respectively, in alignment therewith. It will

be appreciated that if for any reason spaces 182 were not provided, the workpiece would be crushed whereas with the spaces provided this does not occur. In view of the fact that the rolls 162, 170 and 177 are made from polyurethane material, they can yield laterally in the event that a workpiece tends to become jammed between the rolls thereby tending to obviate injury to either the rolls or to the workpiece. In this respect a roll such as 171, 172, 165 or 166 can yield laterally the entire distance to an adjacent roll and then return to its normal position shown in the drawings when the force is released.

Furthermore, it is to be noted from FIGS. 15 and 17 that a comb assembly 184 is secured to the base of the machine and includes tines 185 which extend up between rolls 122. Furthermore, a comb assembly 186 is secured to the upper pivotal frame 144 and includes tines 187 which are positioned between rolls 37 in the same manner that tines 185 are positioned between rolls 22. It will be appreciated that when roll assemblies such as 162 and 170 of FIGS. 19 and 20, respectively, are mounted on a machine such as shown in FIG. 15, with comb assemblies 184 and 186, that in the event a workpiece is stuck between the rolls, the rolls may be yieldable when the tines engage the workpiece to permit the workpiece to be released from its jamming engagement with the rolls, without injury to the rolls.

In FIG. 22 a still further modified bending machine 190 is shown. This embodiment for all practical purposes is extremely similar to the embodiment of the machine shown in FIGS. 1 and 2. Therefore, only a relatively schematic side view has been shown in the interest of brevity. Basically machine 190 includes a base 191 and a pair of spaced upstanding side walls 192 and 193 located one behind the other. Shafts 194, 195 and 196 are essentially journaled between side walls 192 and 193. A source of rotation such as shaft 12 of FIG. 1 is provided for driving a gear (not shown) on shaft 195 which is in mesh with a gear (not shown) mounted on shaft 196 which in turn is in mesh with a gear (not shown) mounted on shaft 197. The gears have been omitted in the interest of simplicity but operate in the same manner as gears 34, 33 and 35 of FIG. 1. Axially spaced rolls such as 22 are mounted on shaft 195 and rolls such as 37 are mounted on shaft 197. Shaft 197 is mounted between spaced arms 198 which are mounted on shaft 196 in the same manner as arms 28 of FIG. 1. Spaced arms 198 form the lower portion of pivotal frame 199 which is analogous to pivotal frame 23 of FIG. 1. A weight 200 is located at the outer end of frame 199. As can be seen, a shaft 201 is mounted on machine 190 in an analogous manner to shaft 16' of FIG. 2, and this shaft carries a disc 202 which mounts an eccentric pin 203 on which block 204 is mounted which in turn receives one end of a turnbuckle-like screw 205, the other end of which is received in U-shaped member 206 which may be the same as member 50 of FIG. 2. A shaft or pin 207 extends through the spaced arms 208 of U-shaped member 206 and also passes through ear 209 which is analogous to ear 47 of FIG. 2. Ear 209 extends outwardly from carrier 210 which is pivotally mounted on shaft 194 and carries a plurality of axially spaced rolls 45 between spaced arm portions 211, rolls 45 being mounted on shaft 212 extending between spaced arms 211.

Up to this point the structure of bending machine 190 is extremely similar to the structure of machine 10 of FIGS. 1, 2, 15 and 17. However, in the structure of FIG. 22 the workpiece is not forced outwardly between rolls 22 and 37 as it is in those figures. In this embodiment a cam 213 is keyed to shaft 201 and rotates therewith. An adjustable cam follower 214 is mounted on slide 215 on pivotal frame 199 so that the latter rises and falls in following the cam. The position of slide 215 is adjustable by moving it in slot 216 and thereafter tightening screw 217. In the position shown in FIG. 22 the cam has raised carrier 199 to its uppermost position so as to provide a relatively large space between rolls 22 and 37. With continued rotation of the cam, the rolls 37 will approach rolls 22 prior to the insertion of a workpiece between the three series of rolls.

At this time rolls 45 which are mounted on carrier 210 will be in a position similar that shown in FIG. 3 so as to permit a workpiece to drop between the series of rolls. In the embodiment of FIG. 22, the cam positively separates the rolls 22 and 37 so as to obviate the necessity for forcing the workpiece through it. In addition to this, it is to be noted that in the event a workpiece gets jammed, the fact that there is no positive connection between the cam follower 214 and 213 will permit carrier frame 199 to pivot in a clockwise direction to provide a larger spacing between rolls 22 and 37. It is to be noted from the position of pin 203 and cam 213 in FIG. 22 that the rolls 37 are caused to move away from rolls 22 while rolls 45 are being moved in a counterclockwise direction about shaft 194. In other words, the rolls 22 and 37 may be caused to remain relatively close to each other while the rolls 45 effect the overbending and subsequent bending of the workpiece. The overbending is effected when rolls 45 reach their limit of clockwise travel and the bending is achieved as rolls 45 recede from the workpiece, and immediately thereafter rolls 37 will move away from rolls 22 to permit the workpiece to drop through the space therebetween. Any of the rolls described above can be used in the embodiment of FIG. 22.

- What is claimed is:
- 25 1. A machine for straightening an elongated workpiece comprising a base, first shaft means mounted on said base, a series of first rolls spacedly and coaxially mounted on said first shaft means, second shaft means laterally offset from said first shaft means and extending in substantially the same direction as said first shaft means, a series of second rolls spacedly and coaxially mounted on said second shaft means with their peripheries in contiguous relationship to said first rolls, third shaft means laterally offset from said first and second shaft means and extending in substantially the same direction as said first and second shaft means, a series of third rolls spacedly and coaxially mounted on said third shaft means with their peripheries in contiguous relationship to the peripheries of said first and second rolls to receive a workpiece to be straightened, said first and second and third rolls including resilient plastic peripheries, axially spaced fourth rolls on said third shaft means having conductive outer rims for contacting spaced portions of a workpiece, and conductor means in engagement with said spaced fourth rims for conducting electricity through a metallic workpiece in engagement therewith.
  - 30 2. A machine for straightening an elongated workpiece as set forth in claim 1 wherein said plastic peripheries on each of said rolls comprises an annular tire-like member.
  - 35 3. A machine for straightening an elongated workpiece as set forth in claim 1 wherein said first, second, and third rolls are fabricated substantially entirely of plastic.
  - 40 4. A machine for straightening an elongated workpiece comprising a base, first shaft means mounted on said base, a series of first rolls spacedly and coaxially mounted on said first shaft means, second shaft means laterally offset from said first shaft means and extending in substantially the same direction as said first shaft means, a series of second rolls spacedly and coaxially mounted on said second shaft means with their peripheries in contiguous relationship to said first rolls, third shaft means laterally offset from said first and second shaft means and extending in substantially the same direction as said first and second shaft means, a series of third rolls spacedly and coaxially mounted on said third shaft means with their peripheries in contiguous relationship to the peripheries of said first and second rolls to receive a workpiece to be straightened, said first and second and third rolls including resilient plastic peripheries, both said first and second series of rolls comprising alternating rolls of first and second diameter with said rolls of said first diameter being slightly larger than the rolls of said second diameter, and said rolls of said first diameter of said first series being positioned in opposition to said rolls of said second diameter of said second series and said rolls of said first diameter of said second series being positioned in opposition to said rolls of said second diameter of said first series.
  - 45
  - 50
  - 55
  - 60
  - 65
  - 70
  - 75

5. A machine for straightening an elongated workpiece as set forth in claim 4 including composite rolls on at least two of said shafts in opposition to each other, said composite rolls have portions of said smaller diameter located in opposition to portions of said larger diameter.

6. A machine for straightening an elongated workpiece as set forth in claim 5 wherein said first, second, third and composite rolls are fabricated substantially entirely of plastic.

7. A machine for straightening an elongated workpiece comprising a base, first shaft means mounted on said base, a series of first rolls spacedly and coaxially mounted on said first shaft means, second shaft means laterally offset from said first shaft means and extending in substantially the same direction as said first shaft means, a series of second rolls spacedly and coaxially mounted on said second shaft means with their peripheries in contiguous relationship to said first rolls, third shaft means laterally offset from said first and second shaft means and extending in substantially the same direction as said first and second shaft means, a series of third rolls spacedly and coaxially mounted on said third shaft means with their peripheries in contiguous relationship to the peripheries of said first and second rolls to receive a workpiece to be straightened, said first and second and third rolls including resilient plastic peripheries, said plastic peripheries on each of said rolls comprising an annular tire-like member, axially spaced fourth rolls on said third shaft means having conductive outer rims for contacting spaced portions of a workpiece, and conductor means in engagement with said spaced fourth rims for conducting electricity through a metallic workpiece in engagement therewith.

8. A machine for straightening an elongated workpiece as set forth in claim 7 comprising first adhesive means between said rolls and said annular tire-like members and first cutaway portions in said rolls for admitting adhesive to provide key-like connections therebetween, insulating rings between said fourth rims and the remainder of said fourth rolls, second cutaway portions between said outer conductive rims and said insulating rings and between said insulating rings and said fourth rolls, and second adhesive means between said fourth rims and said insulating rings and the remainder of said fourth rolls with said second adhesive means being received in said second cutaway portions to define key-like connections therewith.

9. A machine for straightening an elongated workpiece as set forth in claim 1 including gate means effectively located between said first and second rolls at the outlet portion thereof, motor means coupled to said gate means, and control means for selectively energizing said motor means to cause said gate means to assume a position wherein it receives a discharged workpiece and conveys it in a predetermined path.

10. A machine for straightening an elongated workpiece comprising a base, a first shaft mounted on said base, a series of first rolls spacedly and coaxially mounted on said first shaft, a second shaft laterally offset from said first shaft and extending in substantially the same direction as said first shaft, a series of second rolls spacedly and coaxially mounted on said second shaft with their peripheries in contiguous relationship to said first rolls, a third shaft laterally offset from said first and second shafts and extending in substantially the same direction as said first and second shafts, a series of third rolls spacedly and coaxially mounted on said third shaft with their peripheries in contiguous relationship with said first and second rolls to define an opening between said first and second and third rolls to receive a workpiece to be straightened, means for driving said third rolls toward and away from said first and second rolls to provide an opening for

receiving said workpiece and to cause said third rolls to move into engagement with said workpiece, and yieldable means for biasing said second rolls toward said first rolls while permitting said second rolls to yield away from said first rolls upon forcing of said workpiece through the space therebetween by said third rolls during its motion toward said first and second rolls.

11. A machine for straightening an elongated workpiece as set forth in claim 10 including cam means for cyclically causing said second rolls to move toward and away from said first rolls.

12. A machine for straightening an elongated workpiece as set forth in claim 10 wherein said yieldable means comprises a lever pivotally mounted relative to said base means and rotatably mounting said second rolls.

13. A machine for straightening an elongated workpiece as set forth in claim 10 including means for driving said first and second rolls.

14. A machine for straightening an elongated workpiece as set forth in claim 10 wherein said third shaft means are mounted on a second lever, second pivot means for pivotally mounting said second lever relative to said base, and wherein said means for driving said third rolls toward and away from said first and second rolls comprises an eccentric drive mounted relative to said base, link means coupling said eccentric drive to said second lever, and means for varying the length of said link means to adjust the throw of said third rolls.

15. A machine for straightening an elongated workpiece as set forth in claim 12 including stop means for limiting the movement of said lever in a first direction to thereby determine the spacing between said second and first rolls, and means for adjusting the position of said stop means thereby to adjust the spacing between said second and first rolls.

16. A machine for straightening an elongated workpiece comprising a base, a first shaft mounted on said base, a series of first rolls spacedly and coaxially mounted on said first shaft, a second shaft laterally offset from said first shaft and extending in substantially the same direction as said first shaft, a series of second rolls spacedly and coaxially mounted on said second shaft with their peripheries in contiguous relationship to said first rolls, a third shaft laterally offset from said first and second shafts and extending in substantially the same direction as said first and second shafts, a series of third rolls spacedly and coaxially mounted on said third shaft with their peripheries in contiguous relationship with said first and second rolls to define an opening between said first and second and third rolls to receive a workpiece to be straightened, means for driving certain of said rolls, and comb means extending upwardly between certain of said rolls for combing out any workpieces which may become jammed therebetween.

17. A machine for straightening an elongated workpiece as set forth in claim 10 wherein said comb means extend between said first and second rolls.

18. A machine for straightening an elongated workpiece comprising a base, a plurality of adjacent shaft means mounted in substantially parallel relationship on said base, spaced roll means mounted in coaxial relationship on said shaft means with the peripheries of said roll means on said adjacent shaft means being in contiguous relationship to each other to receive a workpiece therebetween, said roll means including resilient plastic peripheries, axially spaced additional roll means on certain of said shaft means having conductive outer rims for contacting spaced portions of a workpiece, and conductor means in engagement with said outer rims for conducting electricity through said workpiece in engagement therewith.
